UNITED STATES PATENT OFFICE

JEHANGIR MANECKJI COOPER, OF BOMBAY, INDIA

PRINTING APPARATUS

Application filed October 26, 1923, Serial No. 670,831, and in Great Britain October 28, 1922.

My invention relates to the printing of patterns or designs upon cloth, paper or any other material and more particularly to printing and the like operations such as coating, 5 varnishing, etc., by the process described in my Patent No. 1,359,034, according to which the printing is produced from a metal color or ink-carrying cylinder having a plain, smooth, hard surface, the pattern or design 10 being carried by another cylinder, the material to be printed on being passed between the said two cylinders.

The machine forming the subject matter of my present invention is provided, in addition 15 to the smooth color, or ink-carrying, cylinder and the pattern cylinder, with means for conducting the web of material around the pattern cylinder, and a color supply duct, the color being in direct contact with the color 20 cylinder without color transferring rollers. A second impression cylinder may be provided by which to print another web of material with the reverse of the pattern, and means for printing from a pattern or design longer 25 than the circumference of the pattern cylinder.

The invention will be more fully described with reference to the accompanying drawing, in which Fig. 1 is a side elevation of one form 30 of the new printing machine, Fig. 2 an end elevation thereof, with parts omitted, Fig. 3 a longitudinal section through the same showing the means for using a continuous pattern, and Fig. 4 a front elevation of the pattern 35 guide roller *p* shown in Fig. 3.

In the frame *A*¹ to rotate in fixed bearings *a* is mounted the color cylinder *A*, and below the same, in movable or adjustable bearings *b*, the pattern cylinder *B*, which can be set at 40 any distance from, or to bear with any desired pressure against, the color cylinder *A*. The bearings *b* may rest upon screws *b*¹, as shown, or on levers or eccentrics by which they can be raised or lowered as required.

45 The cylinders *A* and *B* are geared together, preferably by helical gears to prevent backlash, their peripheries running at uniform surface speed with each other.

Brackets *C* attached to the frame *A*¹ carry 50 a roller *D* upon which the material *E* to be

printed is wound. A winding-on roller *G* is mounted below the roller *D* driven by a chain or band from the pattern cylinder *B* with a slip pulley *g* to compensate for the gradually increasing size of the roll and maintain the speed like that of the surface of the pattern cylinder and thereby keep an even tension on the material *E*. This arrangement is essential to obtain successful results in printing because there must be proper and even tension on the material in its entire traverse through the machine from *D* to *G*. 55

A series of guide rollers *H*, *H*¹, *H*², *H*³ are provided between the roller *D* and the pattern cylinder *B* to assist in maintaining the desired 60 tension on the material *E* which when a clear back-ground is desired should be held tightly stretched around (preferably about three fourths of) the pattern cylinder so that only the part of the cloth lying upon the relief 65 portions of the pattern on the cylinder *B* will be pressed against the film of ink or color on the cylinder *A*, and also that when printing with tacky printers' ink is done the tendency 70 of the cylinder *A* to smear the material by lifting it towards itself will be checked. The roller *H* as well as the others may be scrimp 75 rolls to put tension along the width of the material and to smooth any creases out of the material before reaching the cylinders 80 *A*, *B*. The variation of the length-wise tension of the material to be printed on is effected 85 in any well-known manner, for instance by a weighted roller *H*⁴ bearing on roller *H*³.

The present known method of inking or 90 coloring the printing surface employs a separate ink-duct or color-reservoir, one or more intermediate rollers to transfer the ink or color from the duct to the distributing rollers, and distributing rollers to distribute the ink 95 onto the printing surface. In place of the above separate duct, the duct is formed in my machine directly on the printing surface. The supply of ink or color being thus directly 100 on the printing surface in my machine, the transferring rollers are entirely dispensed with. Furthermore, one roller is sufficient to apply the ink or color directly cooperating with the printing surface. Moreover, certain types of color are thus more efficiently spread.

An ink reservoir or duct is formed by a film producing cylinder K adjacent to and substantially in contact with the cylinder A. The surface of the cylinder K at the point of contact with cylinder A is moved or rotated at a slower speed preferably in the same direction as the cylinder A, or is even maintained stationary to act as a straight edge. Brackets or plates k are fitted to and pressed against the ends of the cylinder A and cylinder K to form the ends of the ink reservoir, and further brackets or plates may be inserted at intervals to provide reservoirs for different colors. As the cylinder A rotates, a thin film of ink or color, of any desired degree of thickness, is evenly distributed over its surface by the cylinder K.

The latter is mounted in adjustable bearings k^2 by which it can be moved toward and away from the cylinder A to regulate the thickness of the film of ink or color carried by the cylinder A. The cylinder K as shown is driven from the cylinder A by a worm gearing L at a greatly reduced speed. A wiper k^1 is applied to the cylinder K to prevent ink or color being carried over the top of the same.

To prevent dust or fluff from being picked up from the material E by the ink cylinder A, a wiper M (Fig. 3) may be applied to the latter with a trough m to collect any surplus ink that is removed.

The printing of the pattern absorbs or removes part of the color from the color cylinder A thus leaving the color thereon as a reverse or negative pattern, and this pattern can be imprinted on to another fabric as a reverse pattern thereon. A plain smooth impression cylinder N, (Figs. 1 and 2) preferably with a resilient surface, is mounted in adjustable bearings behind the color cylinder A over which impression cylinder a second fabric E¹ is passed, this fabric being held taut by any well-known suitable means not shown in the drawing. Thus, two separate webs of material may be printed simultaneously, the pattern on E¹ being the reverse of that on E.

Where a pattern or repeat of a pattern to be printed is longer than the periphery of the pattern cylinder B, an endless band P (Fig. 3) of rubber, thin metal, celluloid, paper, or other suitable material, may be employed to carry the pattern. Or, the pattern itself, if it is a material such as lace or embossed fabric, may be formed into an endless band. A guide roller p is fitted to carry the pattern band P. The latter is passed round the roller p and pattern cylinder B, and the fabric to be printed passes between the pattern band and the color cylinder A. The guide roller p is mounted in adjustable bearings and on adjustable bars to accommodate bands of varying length. To guide the pattern band P straight over the cylinder

B, the roller p is made with inclined flanges p¹, and the band P is kept slack so that should it tend to move laterally in either direction, it will slide down the flanges by its own weight and thus keep to its centre. If the band be too light, a light roller riding on its top will assist it to slide down the flanges. The flanges p¹ are adjustable on the roller p.

The machine may also be adapted to do duplex printing with exact register and from one pattern cylinder by applying ink or color to the latter in which case the pattern cylinder may be an engraved cylinder of gelatine or rubber or the like, or even of metal.

This is accomplished as indicated in Fig. 1 by two cylinders 1K and 1A, which form the two sides of a color duct similar to that formed between the two cylinders A and K. Cylinder 1A is supplied with a uniform film of color, in the same manner as cylinder A, and this color is transferred to the pattern on cylinder B.

The principle of my printing process having been explained in my Patent No. 1,359,034, it is unnecessary to give any further details concerning that process except as to mention that the cylinder B carries the pattern which may be secured to its surface by an adhesive, or otherwise.

The material to be printed on is drawn from the reel by frictional contact between the cylinders A and B.

When printers' ink (oil color) is used, the printed material E may be wound direct onto a reel, but when the ordinary calico color is used, the cloth is first passed over drying cylinders as now in general use.

Various changes in construction and arrangement of parts will be evident to those skilled in the art, as well as various additions and combinations of my new printing machine, and the modifications shown with the same. Therefore, it is to be understood that my invention is not limited to the specific forms shown but is to be considered in the light of the prior art taken in connection with the appended claims.

I claim as my invention:

1. In a printing machine, in combination with a rotatable color cylinder, a continually rotating film producing cylinder maintaining with said color cylinder a supply of color in direct contact with the surface of said color cylinder.

2. In a printing machine, in combination with a rotatable color cylinder, a continually rotating adjustable film producing cylinder maintaining with said color cylinder a supply of color in direct contact with the surface of said color cylinder.

3. In a printing machine, in combination with a rotatable color cylinder, a continually rotating film producing cylinder rotating in the same direction as said color cylinder, thereby continually producing a uniform

smooth film on the surface of said color cylinder.

4. In a printing machine, in combination with a rotatable color cylinder, a continually rotating film producing cylinder adapted to contact with the surface of said color cylinder, thereby maintaining a supply of color directly on said color cylinder, and adjustable bearings for said film producing cylinder.

10 5. In a printing machine, in combination, a rotatable color cylinder having a smooth surface, stationary bearings for said color cylinder, a rotatable pattern cylinder, adjustable bearings for said pattern cylinder, a smooth film producing cylinder for distributing color on said color cylinder in a uniform film, said color and film producing cylinders forming together a color supply duct.

20 6. In a printing machine, in combination with a rotatable color cylinder, a continually rotating film producing cylinder adjacent to and adapted to contact with said color cylinder, said two cylinders forming together a color supply duct in direct contact with said 25 color cylinder, and means for rotating said film producing cylinder in the same direction as said color cylinder.

7. In a printing machine, in combination, a rotatable color cylinder, a film producing cylinder adjacent to and adapted to contact with said color cylinder, said two cylinders forming together a color supply duct, and means for rotating said film producing cylinder in the same direction as, but at slower 35 speed than, said color cylinder.

8. In a printing machine, in combination, a rotatable color cylinder, a film producing cylinder adjacent to and adapted to contact with said color cylinder, said two cylinders forming together a color supply duct, and means for rotating said film producing cylinder in the same direction as, but at a different speed from said color cylinder.

40 9. In a printing machine, in combination, a rotatable color cylinder, a film producing cylinder adjacent to and adapted to contact with said color cylinder, said two cylinders forming together a color supply duct, means for rotating said film producing cylinder, and 50 a wiper to prevent color from passing around on said film producing cylinder.

10. The method of printing, which comprises applying color to a smooth surface, then passing said surface into contact with 55 the material to be printed, while the material is held under tension both lengthwise and crosswise against a pattern, so that part of the color is transferred from said surface to the raised portion of said material and 60 then passing said surface into contact with a second material adapted to remove the remainder of the color from said surface, whereby the reverse pattern is printed on said second material.

65 11. In a printing machine, in combination,

a color cylinder, means to apply a uniform film of color to said color cylinder, a pattern cylinder, means to pass material to be printed between said pattern cylinder and said color cylinder, a smooth surface cylinder, adjustable bearings for said smooth surface cylinder, and means to pass a second material between said smooth cylinder and said color cylinder, so as to print on said second material a design the reverse of that printed 75 on the first material.

12. In a printing machine, in combination, a color cylinder, means to apply a uniform film of color to said color cylinder, a pattern cylinder, means to pass material between 80 said color cylinder and said pattern cylinder, and means to apply color to said pattern cylinder to simultaneously produce impressions on both sides of the material to be printed in exact register with each other.

85 13. In a printing machine, in combination, a color cylinder, a film producing cylinder adjacent to and substantially in contact with said color cylinder, a color duct formed by and between said cylinders a pattern cylinder, means to pass material to be printed between said pattern cylinder and said color cylinder, and means to hold the material to be printed under uniform tension lengthwise and crosswise to prevent the portions not 90 raised by the pattern from coming into contact with the color cylinder.

In testimony whereof I affix my signature.
JEHANGIR MANECKJI COOPER.
